BASE BLOCK FOR CRUCIBLES OR THE LIKE

George T. Hubbell, West Haven, Conn., assignor
to American Crucible Company, Shelton, Conn.,
a corporation of Delaware

Application December 10, 1942, Serial No. 468,533

4 Claims. (Cl. 263—11)

This invention relates to base blocks for crucibles, and more particularly to a supporting device for a crucible to support the latter within a furnace so that it will be efficiently and evenly heated, particularly over the bottom portion thereof, while at the same time the flame of the burner will not be permitted to contact the bottom of the crucible directly.

Crucibles employed in foundry work are composed of a material which may be approximately fifty percent graphite and the remainder silicon carbide and clay. Usually the side walls of the crucible are glazed with a flame-resisting material, but the bottom is left unglazed. For this reason it is not desirable that the flame contact the bottom of the crucible directly, or the graphite will be oxidized.

It is, however, desirable that the bottom of the crucible be evenly heated, and particularly that it be heated to the same extent as the side walls so that unequal expansion and cracking of the crucible will not result. It has been proposed in the past to place the crucibles on supports which have a solid top portion, thus preventing the flame from contacting the body of the crucible. Such a support or base block, however, does not permit the hot gases from the flame to contact the bottom of the crucible, but rather tends to insulate this portion of the crucible from the heated gases so that it does not receive as much heat as the side walls. This not only does not accomplish effective melting of the material in the crucible, but heats the latter unevenly with undesirable results.

One object of the present invention is the provision of a base block for crucibles which will permit the hot gases of the furnace flame to contact directly with the bottom of the crucible, but at the same time will prevent the flame itself from contacting this portion of the crucible.

Another object of the invention is the provision of a base block for crucibles so formed that the bottom of the crucible will be subjected directly to the hot gases of the flame for efficient heating, but will not be subjected to the flame itself, thus preventing oxidation of the material of which the crucible is made.

A still further object of the invention is the provision of a base block for crucibles comprising a lower base portion having thereon a plurality of upstanding spaced supporting members so formed that when the flame is applied to the block in one direction, for example, a clockwise direction, it will tend to pass around the exterior of the block, while the hot gases from the flame

will be permitted to enter the spaces between the supporting members and attack directly the bottom of the crucible.

Still another object of the invention is the provision of a base block for crucibles provided with a solid base portion and a plurality of upstanding supporting members thereon, such that when a crucible is supported on the supporting members the furnace flame will not enter the spaces between the supporting members when the flame is applied to the furnace in one direction, but will tend to cause the flame to enter the spaces between the supporting members when the base block is inverted and the crucible is supported upon the base portion of the block.

To these and other ends the invention consists in the novel features and combinations of parts to be hereinafter described and claimed.

In the accompanying drawing:

20 Fig. 1 is a sectional view of a furnace and a crucible supported on a base block embodying my invention;

Fig. 2 is a sectional view on line 2—2 of Fig. 1;
Fig. 3 is a top plan view of the base block;

Fig. 4 is a side view of the block; and
Fig. 5 is a sectional view on line 5—5 of Fig. 3.

To illustrate a preferred embodiment of my invention, I have shown in a conventional manner a furnace 10 having a lining 11 and a bottom portion 12, which parts 11 and 12 will normally be made of refractory material. The wall of the lining 11 may be provided with an opening 13, shown in dotted lines in Fig. 2, and it may be observed that this opening is obliquely formed

35 in the wall of the crucible so that the flame from the burner nozzle placed in this opening will be directed substantially tangentially to the space between the furnace lining and the supporting block, as will be hereinafter described.

40 Within the furnace is disposed a crucible 14 which rests on a base block 15, there being a sufficient annular space remaining between the side wall of the furnace and the crucible and block upon which it rests. As will be seen from Fig. 2, the opening 13 is directed substantially tangentially to the block 15 so as to direct the flame around the block in the space between the latter and the furnace lining.

45 The base block 15 is made of refractory material so as to withstand the heat of the flame, and comprises a base portion 16, which, in the form of my invention shown, is substantially circular in shape, and a plurality of upstanding supporting members 17, there being four of these members, 50 as shown in the drawing, although the exact

number is not material. It will be noted that these members are spaced from each other both at the center of the base block 16 and also between the side walls of the supporting members, as shown at 18, so as to permit the hot gases from the flame to enter the spaces 18 and circulate freely therethrough in direct contact with the bottom of the crucible 14.

The members 17 are curved from their inner portions outwardly, and particularly at their outer end portions, so that the flame entering the space about the block through the opening 13 will tend to be directed about the periphery of the block and restrained from entering the spaces 18, so that the flame will not come in contact with the bottom or base of the crucible. As shown in Fig. 2 of the drawing, the flame is directed in a clockwise direction, and correspondingly, as shown in Fig. 3, the elements 17 are so shaped that when the flame tends to pass around the base block in a clockwise direction it will continue in this path and will not be deflected through the spaces 18. If it is desired to use a similar block with a furnace in which the flame is directed in a counter-clockwise direction, the elements 17 would be reversed with respect to their direction of curvature shown in Fig. 3.

While the exact shape of the member 17 is not important in all aspects of the invention, I have found that a very efficient structure results when both of the lateral surfaces of these elements are formed along the arcs of curves. For example, as shown in Fig. 3, the shorter wall $a-b$ of one of the members 17 may be formed on the arc of a curve having its center at c , which center is midway between the ends of a radius $x-x'$ of the base block 16. The radius of the arc $a-b$ which has been chosen is one half that of the radius of the block, so that if the curve $a-b$ were continued it would pass through the center of the block, and also be tangent to the periphery of the block. The longer wall of the member 17 is formed of a similar curve $d-e$ having its center at the point f on a radius $x-y$ 60° from the radius on which the point c is located, this curve having the same radius as the curve $a-b$. However, from the point e the wall is continued to the point g , following the periphery of the base portion 16 from the point e to the point g . A suitable opening is left between the inner ends of the members at the center x of the base portion 16, and the ends of the members 17 are rounded off, the curves of the ends merging into the two curves of the side walls, as explained above. This forms these supporting members of a substantially tear-drop shape, so that they will tend to cause the flame directed into the space between them and the furnace wall to sweep around their outer peripheries instead of passing into the spaces between them.

The face $a'-b'$ of the next supporting member 17 is formed about a center on a radius $x-z$, which radius is at an angle 30° to the radius $x-y$, and this process is continued about the block. Preferably the upstanding supporting members 17 are formed integrally with the base portions thereof, although this is not imperative. It is, however, desirable to have them secured to the base portion 16 so that they will always occupy the proper positions with respect to the block and with respect to each other to prevent the flame coming in contact with the bottom of the crucible.

In some instances it is desired to have the

crucible supported upon a solid base, but to provide for the flame, even if tangentially directed, to enter below this base so that the bottom of the crucible will be evenly heated and the base itself will prevent the flame from coming in contact with the bottom of the crucible. To effect this result it is merely necessary to turn the base block illustrated upside down with respect to the position shown in the drawing herein. When the base block is thus reversed, the crucible will rest upon the solid portion 16, and the direction of the curvature of the supporting members 17 will in effect be reversed. That is, the outer ends of these members will point in a direction opposite to that shown. As will be clearly seen from Fig. 2, a flame entering through the opening 13 when the base block is inverted will tend to enter the spaces 18 between the member 17, and thus pass directly below the base portion 16, heating it evenly and likewise heating the bottom of the crucible evenly and efficiently. Therefore, whether the particular operation which is to be carried out is best served by having the flame pass around the base block, or pass through the spaces below the block, either effect may be accomplished by using the device illustrated in upright or inverted position, while in either position the bottom of the crucible is evenly heated and the flame is prevented from coming in direct contact therewith.

The base block will be made of a suitable refractory material to withstand the high temperature of the burner flame, and will usually be made of a silicon carbide clay-bonded refractory material, although its particular composition is not of importance in all aspects of the invention.

While I have shown and described a preferred embodiment of my invention, it is to be understood that it is not to be limited to all of the details shown, but is capable of modification and variation within the spirit of the invention and within the scope of the claims.

What I claim is:

1. A base block for supporting crucibles or the like in the heating chamber of a furnace, comprising a circular base portion having upstanding spaced supporting members on one face thereof, each of said members extending from a point adjacent the center of the base portion to a point adjacent the periphery thereof, and said members being correspondingly curved adjacent their outer ends to direct a flame around the outer ends of said members when said flame is directed around the block in one direction and to cause the flame to enter the spaces between said members when the flame is directed around the block in the opposite direction, said block being adapted to rest freely on the floor of the heating chamber and being reversible in position to rest either on the base portion or on said members.

2. A furnace comprising a heating chamber having, adjacent the base, a tangentially disposed burner inlet opening, a base block adapted to support a receptacle for the material to be heated, and resting freely on the floor of the chamber and reversible top for bottom thereon, the periphery of said block being spaced from the wall of the chamber opposite to said opening, said block comprising a base portion having spaced upstanding receptacle supporting members thereon, and said members extending from a point adjacent the center of the block to the periphery thereof and having their outer ends

curved in a direction to cause the flame to pass around said members when applied to the block in one direction and to enter the space between said members when applied to the block in the opposite direction.

3. A furnace comprising a heating chamber having, adjacent the base, a tangentially disposed burner inlet opening, a base block adapted to support a receptacle for the material to be heated, and resting freely on the floor of the chamber and reversible top for bottom thereon, the periphery of said block being spaced from the wall of the chamber opposite to said opening, said block comprising a base portion having spaced upstanding receptacle supporting members thereon, said members extending from a point adjacent the center of the block to the periphery thereof and having their outer ends curved in a direction to cause the flame to pass around said members when applied to the block in one direction and to enter the space between said members when applied to the block in the opposite direction, and said members having one

side wall convexly curved and the opposite side wall concavely curved.

4. A base block adapted to be inserted in and removed from a circular furnace chamber having a substantially tangentially extending burner opening, said base block being adapted to support a receptacle for material to be heated and substantially coaxial therewith, and comprising a circular disc portion and a plurality of flanges 10 on one face thereof, said flanges being spaced apart at the center of said block and along their lengths, the opposed surfaces of said flanges defining passages with their outer ends facing substantially tangentially of the block, whereby 15 when said block is inserted one side up in said furnace opposite to said burner opening, the flame from said burner opening will in part enter said passages, and when said block is inserted the other side up, substantially all of the flame will tend to flow past the outer ends of 20 the passages without entering the same.

GEORGE T. HUBBELL.
